UNITED STATES PATENT OFFICE.

PETER CHARLES SHERNER, OF OGDEN, UTAH.

AEROPLANE.

1,302,864.

Specification of Letters Patent.

Patented May 6, 1919.

Application filed October 12, 1917. Serial No. 196,161.

To all whom it may concern:

Be it known that I, PETER C. SHERNER, a citizen of the United States, and a resident of Ogden, in the county of Weber, and State 5 of Utah, have invented a new and useful Improvement in Aeroplanes, of which the following is a specification.

My present invention relates particularly to aeroplanes and has to do generally with 10 the propulsion thereof, my object being to utilize as an assistance in the propulsion as well as stability of the machine, certain air currents developed in its normal operation.

I have found that in the normal operation 15 of an aeroplane, certain air currents are projected forwardly over the rear extremity of the wing or wings of the machine, and I propose the addition of certain means in connection with the wings of aeroplanes, 20 whereby to take advantage of these air currents and bring about their assistance to the propulsion as well as to the stability of the machine.

More particularly my invention aims to 25 provide an adjustable wind vane in connection with an aeroplane wing, and adjustable with respect thereto, at a point where the air current directed forwardly over the rear extremity of the wing will engage the vane 30 and by their engagement, assist in the propulsion of the machine and the stability thereof, without increasing the normal wind resistance.

Another object of the invention is the provision of means which will control the effect 35 of air currents against the wind vane and obviate excessive pressure thereagainst.

My invention specifically resides in the features of construction, arrangement and 40 operation to be now described with respect to the accompanying drawings, forming part of this specification, and wherein:

Figure 1 is a front elevation of a machine to which my invention is applied,

Fig. 2 is a vertical transverse section taken therethrough substantially on line 2—2 of Fig. 1,

Fig. 3 is a top plan view of the machine,

Fig. 4 is an enlarged transverse section 50 through one of the wings equipped with my improvement.

Fig. 5 is a top plan view illustrating a modified form, and

Figs. 6 and 7 are vertical sections taken

respectively on lines 6—6 and 7—7 of Fig. 55 illustrating different positions of the parts.

Referring now to these figures, I have shown in Figs. 1, 2 and 3 a substantially conventional type of aeroplane, in the present instance, a biplane, the wings appearing at 60 10, the fuselage at 11, the rear rudders, both horizontal and vertical, appearing at 12, and the aileron of the upper wing 10 appearing at 13.

In the normal operation of a machine for 65 instance, of the type just mentioned, I have found that the air currents passing rearwardly beneath one or both of the wings, or at least a part of such air currents as indicated at 14 in Fig. 4, are directed upwardly 70 around the rear ends of the wings, and it is these air currents I aim to utilize for the purposes first above mentioned.

To do this I provide a wind vane 15 consisting of a substantially flat, elongated and 75 relatively rigid body superposed upon the upper surface of the respective wings of the machine along the rear portions thereof, the forward end of this vane 15 being hinged at 16 to the wings 10 so as to permit of vertical 80 adjustment of the rear edge of the vane with respect to the rear edge of the wing.

Between the upper surface of the wings and the lower surfaces of the vane 15 are interposed one or more springs 17 which operate to normally shift the vane on its hinges 85 away from the wings, such shifting movements being under control of one or more flexible connections 18, which latter may be from the operator's station as indicated at 90 19 in Fig. 2.

To better enable the vane 15 to intercept the whole currents of air around the rear ends of the wings, I may employ a flexible 95 web 20, secured at one end to the lower surface of the vane and at its opposite end to the upper surface of the wing, and of sufficient width so that considering its flexibility, the vane 15 may be given a substantially wide range of adjustment with respect to the wing.

It is obvious that as seen in Fig. 2 in particular, both wings of an aeroplane of the biplane type may be provided with my improvement, or only one of such wings, and 105 that the improvement may be provided in connection with selected wings of machines of other types. It is further obvious that

my improved vane may be extended along the entire length of the wings in some instances, or, in connection with wings having ailerons 13 as seen in Fig. 3, my improved 5 vane may be extended for the full length of the wings between said ailerons.

It is to be further understood that, irrespective of whether or not my improvements are capable of materially adding to 10 the speed of movement of an aeroplane, they are calculated to increase the stability thereof, and capable of adjustment not only to vary the degree of their effect, but to collapse the same tightly against the upper face 15 of the wings to a wholly inoperative position.

As seen in Figs. 5, 6 and 7 I may provide each wind vane with a series of trap doors 21 in suitable numbers and in a longitudinal 20 series to normally cover openings through the wind vane between its free edge and the web 20. These trap doors 21 are hinged at one edge at 22 to the wind vane 15 to open vertically in an upward direction 25 with respect to the wind vane and to close downwardly and tightly over the respective opening or openings of the wind vane in normal position. The opening movement of each of the trap doors 21 with respect to 30 the wind vane and the degree of such opening movement is regulated by a bolt or bolts 23 of each trap door, having a hinge connection at its upper end to the trap door and extending downwardly through the 35 wind vane as best seen in Fig. 6 and supporting a spring 24 around its lower portion bearing upwardly against the lower surface of the wind vane. Thus the degree of resistance that the trap door may offer to the 40 air currents is controlled by the strength of the spring 24 and may be regulated by increasing or decreasing the tension of said spring. The spring 24 may be suitably supported in connection with the bolt and the 45 wing 10 in connection with which the wind vane is utilized, may have pockets or other suitable recesses as indicated in Figs. 6 and 7 to receive the lower portions of the bolts 23 when the vane 15 is closed downwardly 50 and tightly against the wing.

Furthermore, although I have shown the wind vane 15 substantially flat in each instance, it is to be observed that I may desire to utilize the same in good form, either 55 with or without the trap doors last described, to follow more particularly the curvature of the wing, and that, although I have shown the rear free edge of the vane in Figs. 2 and 4 terminating in substantially 60 the same vertical plane with the rear edge of the wing 10 in connection with which it is utilized, the rear edge of the wing may be terminated forwardly of the rear edge of the wing and at any suitable distances with 65 respect thereto.

Particular attention should, however, be called to the fact that my invention aims to produce action from forwardly moving air currents and that it is of the first importance to avoid interference with rearwardly 70 moving air currents. To this end it should be noted that the vane 15 is hinged to the downwardly sloping rear portion of a curved wing 10 and although normally outstanding under tension of spring 17, in spaced relation 75 to the wing 10, it does not in any case, or at any point, extend above the horizontal level of the crown of the wing. This is all plainly apparent from a comparison of Figs. 2, 4, 6, and 7. 80

I claim:

1. An aeroplane having a rearwardly and downwardly curved wing provided with a wind vane consisting of a substantially rigid elongated body superposed upon the upper face of the wing along its rear portion, said vane having its forward edge hingedly connected to the wing and having its rear edge movable vertically with respect to the wing, said vane being located and extending in its 90 various positions of adjustment with respect to the wing, wholly below the horizontal level of the crown of the wing and thus providing an obstruction to forwardly moving air currents over the upper rear surface of 95 the wing without interfering with rearwardly moving currents thereover.

2. An aeroplane having a rearwardly and downwardly curved wing provided with a wind vane consisting of a substantially rigid elongated body superposed upon the upper face of the wing along its rear portion, said vane having its forward edge hingedly connected to the wing and having its rear edge movable vertically with respect to the wing, 100 said vane being located and extending in its various positions of adjustment with respect to the wing, wholly below the horizontal level of the crown of the wing and thus providing an obstruction to forwardly moving 105 air currents over the upper rear surface of the wing without interfering with rearwardly moving currents thereover, and means to adjust the rear free edge of the vane with respect to the wing. 110

3. An aeroplane having a rearwardly and downwardly curved wing provided with ailerons adjacent the ends thereof, a wind vane consisting of a substantially rigid elongated body superposed upon the upper face 120 of the wing along its rear portion, said vane having its forward edge hingedly connected to the wing and having its rear edge movable vertically with respect to the wing, said vane being located and extending in its various positions of adjustment with respect 125 to the wing, wholly below the horizontal level of the crown of the wing and thus providing an obstruction to forwardly moving air currents over the upper rear surface of 130

the wing without interfering with rearwardly moving currents thereover.

4. An aeroplane having a rearwardly and downwardly curved wing, a wind vane disposed upon the rear portion of the upper face of said wing and hingedly connected at its forward edge to the wing, and a spring interposed between the wing and the vane to normally shift the latter away from the wing, and a flexible controlling connection secured to the vane for shifting the latter toward the wing and against the tension of said spring, said vane being disposed and movable in its various positions of adjustment wholly beneath the horizontal level of the crown of said spring, whereby to provide a resistance surface to forwardly moving air currents above the wing without obstructing rearwardly moving air currents thereover.

5. An aeroplane having a wing provided with a substantially rigid wind vane extending upon its upper face and along its rear portion, said vane having its forward edge hingedly connected to the adjacent portion of the wing and having its rear free edge adjustable vertically with respect to the rear edge of the wing, means to control said vane, and a flexible web connecting the vane and wing and located approximately midway between the front and rear edges of the vane, for the purpose described.

6. An aeroplane having a rearwardly and downwardly curved wing provided with an adjustable vane extending along the rear portion of the upper face of the wing, said vane being located and having adjustable movement with respect to the wing wholly beneath the horizontal level of the crown of said wing whereby to intercept forwardly moving air currents without obstructing rearwardly moving air currents.

7. An aeroplane having a rearwardly downwardly curved wing provided with means disposed upon the rear portion of the upper face thereof to intercept air currents moving forwardly around the rear edge of the wing, said means having a limited movement with respect to the wing

wholly below the horizontal level of the crown of the wing, for the purpose described.

8. An aeroplane having a wing provided with a wind vane extending along the upper rear portion of the wing and hingedly connected at its forward portion thereto, with its rear edge movable vertically with respect to the upper surface of the wing, said vane having an opening therethrough and spring controlled means normally closing the opening to regulate the pressure against the vane in use.

9. An aeroplane having a wing provided with a wind vane extending along the upper rear portion of the wing and hingedly connected at its forward portion thereto, with its rear edge movable vertically with respect to the upper surface of the wing, said vane having an opening therethrough, a trap door hinged to the vane for normally closing said opening, and yielding connections between the trap door and the vane normally resisting opening movement of the former whereby to control the pressure acting against the wind vane in use.

10. An aeroplane having its wing provided with means along the rear upper surface thereof to intercept air currents extending forwardly and upwardly around the rear edge of the wing and means carried by said first named means to automatically control the effective pressure of the air currents thereagainst.

11. An aeroplane having a rearwardly and downwardly sloping wing provided with means upon the upper surface of its lower rear portion and located below the horizontal level of its crown, to intercept air currents moving forwardly around the rear edge of the wing, and means forming a part of said first named means to automatically control the effective area of said first named means.
